UNITED STATES PATENT OFFICE.

WILLIAM N. AMORY, OF NEW YORK, N. Y.

SHOCK-ABSORBER FOR VEHICLES.

1,341,407.

Specification of Letters Patent. Patented May 25, 1920.

Application filed June 9, 1919. Serial No. 302,896.

To all whom it may concern:

Be it known that I, WILLIAM N. AMORY, a citizen of the United States, residing at New York, in the county and State of New York, have invented certain new and useful Improvements in Shock-Absorbers for Vehicles; and I do hereby declare the following to be a full, clear, and exact description of the invention, such as will enable others skilled in the art to which it appertains to make and use the same.

My present invention relates to an improved and novel construction for use upon aeroplanes, automobiles, and, indeed, vehicles of all kinds, whereby shocks and vibrations due to travel over rough surfaces are absorbed or dissipated. In its application to aeroplanes, my improvement successfully relieves the aviator from the shock incident to landing or, at least, greatly lessens its effect.

It is a valuable characteristic of my present invention that it serves to resist both the primary upward blows or thrusts due to rough roads and the secondary shock due to rebound and exerted in the opposite direction. Furthermore, I accomplish this by the use of a single pneumatic cushion with resilient walls arranged to yield horizontally or at right angles to the direction of impact.

In my pending application for United States patent I have described and claimed means whereby a single pneumatic cushion may be made available for receiving and dissipating or absorbing vibrational shocks, both primary and secondary; that is to say both the original blow and the one or more rebounds that result therefrom.

My present invention has relation to an improvement upon the apparatus in question, wherein means are provided to distribute the blows over portions of the cushion not in the direct line of shock, and preferably to accomplish such distribution over the entire upper and lower areas of the cushion.

The invention is illustrated in a preferred form in the accompanying drawings wherein Figure 1 is a rear elevation of a shock absorber in place, Fig. 2 is a side elevation of the same, a portion being broken away and a portion in vertical elevation, Fig. 3 is a plan and Fig. 4 an edge view of a pressure distributing plate, Fig. 5 is a plan view of a sound deadening disk,

Fig. 6 is a plan view of a preferred form of shock absorbing cushion, and Figs. 7 and 8 are end views of the two shock transmitting elements separated and placed side by side 60 in their normal angular relation.

The shock absorber comprises essentially a pneumatic cushion and two shock transmitting elements connected respectively to the upper end and lower vehicle members, 65 and so placed relative to each other and to the cushion as to transmit pressure to the cushion whether exerted downward or upward thereon. In addition my present invention comprises means whereby the pressures so transmitted are distributed over those parts of the cushion not in direct line with the pressure plates active at a given moment—and preferably over the entire surface of the cushion.

My shock absorber may be given a variety of locations with respect to the vehicle parts, as will be well understood by those skilled in the art. In the particular preferred form shown I have shown it interposed between the frame 10, attached to or forming part of the upper vehicle member, and the end of a spring 11 attached to the lower member or running gear.

The specific construction of the preferred shock transmitting elements will be best understood by reference to Figs. 1, 2, 7 and 8. The shock transmitting element attached to the upper vehicle member 10 will be referred to herein, for convenience, as the upper element, and the second or coöperating element will be called the lower element. It will, of course, be understood that these elements may be interchanged or inverted without change of function, and without departing from the invention.

In the form shown the upper element comprises a central spindle 12 (preferably tubular) provided at one end with a yoke 13 whereby it may be attached, as shown, to the frame 10. Near one end of the spindle, and just under the yoke, there project horizontally and in diametrically opposite directions, two pressure-sectors 14 and 15; and directly beneath these, near the opposite end of the spindle, two exactly similar pressure-sectors project from the spindle, as at 16 and 17.

The lower element is fastened to the spring 11 by the yoke 18 (Fig. 1) which is prolonged upward in the form of two opposed sector-shaped parts 20 and 21, to

gether forming a central hollow stem cut away on opposite sides. Within this hollow stem the spindle 12 of the upper element fits, so as to slide easily up and down, and through the cut-away portions between the parts 20 and 21, the pressure sectors, 14, 15, 16 and 17, radiate.

Projecting in opposite directions outwardly from the parts 20 and 21 of the lower element stem, are the two pairs of pressure-sectors 22, 23, and 24, 25. These correspond in horizontal positions with the pairs of sectors 14, 15 and 16, 17 on the upper element; and the dimensions of the various sectors are such that the pair 14, 15 forms a complete circle with the pair 22, 23, while the pair 16, 17 forms a second circle with the pair 24, 25.

Between the two complete circles thus formed, there is placed the inflatable pneumatic cushion 26, which receives the shocks from the transmitting sectors, converting them into horizontally exerted stresses tending to distend the cushion horizontally outwardly and inwardly toward the stem or axis of the device. This cushion is preferably made in substantially toric form as shown in Fig. 6, and is preferably interrupted as at 27, to permit of its being pressed into place between the shock transmitting sectors and past the stem of the two elements.

It will be readily seen that the cushion, in this position, will receive and absorb the energy of blows delivered either from above or below by either the upper or lower vehicle member.

Fig. 1 illustrates the relative displacement of the sectors either when a shock is delivered from below by the sectors 24 and 25, or from above by the sectors 14 and 15. Obviously displacement in the opposite direction would result upon the reaction or rebound following either of such blows.

It will be seen that in any case the cushion is squeezed or clipped between opposing sectors out of line with each other as viewed vertically. This implies a certain bending or distortional strain transversely to the cushion, and it is the principal object of the present invention to do away with this tendency, and to provide means whereby the shocks transmitted through the various sectors are distributed over preferably the entire surface both above and below the cushion.

For this purpose distributing plates 28 and 29 are placed immediately over and under the cushion 26, and these plates preferably take the form shown in Figs. 3 and 4. As there shown, each plate is in the form of an annular disk having a central circular aperture 30 fitting around the stem 21. It will be seen that, by using distributing plates of this general character, the pressure ex-

erted over a limited sector-shaped area by the transmitting sectors above and below the cushion is distributed over the entire circle. This causes the cushion to be always compressed between directly opposed pressure plates, and eliminates all distortion, besides removing all danger of cutting or pinching the cushion by or between the edges of the relatively displaced sectors.

In Figs. 1 and 2 the plates 28 and 29 are shown as simple uncovered metal plates. In order to avoid the rattling noise which might result from the rapid blows of the metal sectors against the metal plates, padding may be used. This may take the form of rubber surfaces 31 cemented on one or both sides of the plate (see Fig. 4) or separate rubber (or equivalent) pads 32 may be introduced between the distributing plates and the transmitting sectors. As shown in Fig. 5, such a pad should be slit, as at 33, to permit it to be set in place around the stem 21.

In order that the plates 28 and 29 may be placed around the stem 21 as above described, it is preferred to construct each annular plate of two halves overlapping, for instance, as shown at 34 in Fig. 4. These halves having been joined from opposite sides of the stem 21, may be fastened together by various means. For instance, the overlapping portions may be brazed together or electrically welded. If desired, these parts may be riveted together, and, to facilitate this operation, one or more of the transmitting sectors may be provided with apertures 35 (see Fig. 7) permitting sufficient access to the plates 28 and 29. Through these apertures these plates may be riveted on one side of the opening 30 at a time. Obviously, as soon as one plate, as 29, has been thus fastened, the other plate can be similarly put together in the same way.

While I have shown four shock transmitting sectors on each face of the cushion, it will be obvious that a greater number can readily be employed in this connection, if desired.

Various changes may be made in the construction shown, without departing from the scope of my invention, and I do not limit myself to the details herein shown and described.

What I claim is—

1. A shock absorbing device for vehicles comprising a pneumatic cushion, means adapted to transmit vibrational shocks from two directions over parts of the upper and lower surfaces of said cushion, and means adapted to receive the direct impact of the first named means and distribute the same over substantially the entire upper and lower cushion surfaces.

2. A shock absorbing device for vehicles comprising a pneumatic cushion, opposed

- pairs of shock transmitting sectors forming a part of an upper member and opposed pairs of similar sectors lying normally side by side with said first named sectors and 5 adapted to slide past them, a pneumatic cushion between opposed pairs of sectors, and distributing plates interposed between said sectors and said cushion on both faces of said cushion.
- 10 3. The construction set forth generally in claim 2 hereof, wherein the sectors forming part of one member are fixed to a hollow stem and the other sectors are fixed to a central spindle adapted to slide within said 15 stem.
4. The construction set forth generally in claim 3 hereof, wherein the distributing

plates are composed of halves suitably connected and spanning the hollow stem.

5. The construction set forth generally in 20 claim 2 hereof, wherein sound deadening pads are interposed between the transmitting sectors and the distributing plates.

6. The construction set forth generally in 25 claim 5 hereof, wherein the sound deadening pads take the form of facings fixed to the outer surfaces of said distributing plates.

7. The construction set forth generally in 30 claim 2 hereof, wherein each set of transmitting sectors moving together is provided with a yoke for attaching the same to its appropriate vehicle member.

In testimony whereof I affix my signature.
W. N. AMORY.
